MULTIPLE UNIVERSAL VENDING MACHINE FOR VENDING SOLID AND LIQUID BODIES

Filed April 4, 1933

Fig. 1.

UNITED STATES PATENT OFFICE

2,044,110

MULTIPLE UNIVERSAL VENDING MACHINE
FOR VENDING SOLID AND LIQUID BODIES

Charles Walker, Knoxville, Tenn.

Application April 4, 1933, Serial No. 664,365

9 Claims. (Cl. 194—61)

My invention consists in new and useful improvements in coin controlled mechanism for vending machines and has for its object to provide a device which may be adapted for various types of machines for vending both articles and liquids. For example, the device may be employed in connection with machines for vending apples, oranges and other fruits, or packages containing various products or articles of manufacture, or it may be used in connection with machines for pumping predetermined quantities of liquid to be vended.

Another object of my invention is to provide a mechanism of this character particularly adapted for vending varying quantities of merchandise according to the denomination of the coin inserted. In other words, the machine is equipped with means for receiving coins of varying denomination, such for example as 5¢, 10¢ and 25¢ pieces, and for automatically vending a quantity of merchandise commensurate with the coin inserted.

A further object of my invention is to provide a coin controlled mechanism embodying a prime mover in the form of a rotary drum provided with a plurality of coin receiving recesses of suitable dimensions to receive coins of different denomination, and means cooperating with an inserted coin for controlling the number of revolutions of the drum according to the denomination of the inserted coin.

With the above and other objects in view which will appear as the description proceeds, my invention consists in the novel features herein set forth, illustrated in the accompanying drawing and more particularly pointed out in the appended claims.

Referring to the drawing in which numerals of like character designate similar parts throughout the several views,

Fig. 1 is a longitudinal sectional view of one form of my improved coin controlled mechanism.

Fig. 2 is a transverse sectional view taken on line 2—2 of Fig. 1, and

Fig. 3 is a sectional view of a modified form of my invention.

In the drawing, referring to Figs. 1 and 2, numeral 1 represents a drum or cylindrical member rotatably mounted in suitable bearings 2 carried by suitable supports 3 and 4 within the casing 5 of a vending machine. A crank arm handle 6 is operatively connected to the drum 1 at one end of its axis and projects through the casing 5 as clearly shown in Fig. 1. At the other end of the axis of the drum 1 I provide a disc 7 rotatable

with the drum, having eccentrically journaled thereon one end of a crank arm 8, the other end of which may be operatively connected either to a liquid vending pump or other vending mechanism.

Adjacent one end of the drum 1 and located above the latter, I provide an arm 9 which is pivoted to the support 4 as at 10 and extends longitudinally of the drum in spaced relation thereto. The free end of this arm terminates in a downwardly projecting lug 11 which is adapted to normally engage a transversely elongated peripheral recess 12 in the drum 1 under the tension of spring 9' mounted in the support 4.

Adjacent one end of the drum 1, I provide a transverse coin receiving recess 13 adapted to receive a coin of the lowest denomination for which the machine is intended to be used, such for example as a five-cent piece shown in dotted lines at 13'. This recess is of a suitable depth to retain an inserted coin in upright position with a portion of the latter extending beyond the periphery of the drum in line for engagement with the underside of the arm 9 as the drum rotates.

Thus, as the handle 6 is turned in clockwise direction, in the absence of a coin from the slot 13, the end of the recess 12 will engage the lug 11 and stop the rotation of the drum. On the other hand, with a suitable coin inserted in the slot 13, the rotation of the drum brings the coin 13' into engagement with the underside of the arm 9 as shown in Fig. 2, whereupon the continued rotation of the drum and coin rocks the arm 9 upwardly on its pivot 10 and disengages the lug 11 from the recess 12. When the drum has completed one-half of a rotation, the recess 13 has reached the lower side of the drum and the coin drops into a suitable receptacle not shown, and by the time the other half of the rotation is completed, the lug 11 drops back into the recess 12 and prevents further rotation of the drum.

At an intermediate point in the drum 1, I provide a second coin receiving slot 14 adapted to receive an intermediate denomination of coin 14' such for example as a ten-cent piece. This recess is considerably deeper than the recess 13 and is provided in its bottom with a plunger 15 normally retained in a predetermined position as shown in Fig. 1 by a coil spring or the like 16, whereby a coin inserted in the slot 14 is sufficiently elevated to operatively engage the arm 9 as in the case of the coin 13'.

Naturally the quantity of merchandise to be vended for a ten-cent piece would be twice that to be vended for a five-cent piece, and it is neces-

sary for the drum 1 to make two complete revolutions. Hence I have provided means for retaining the coin 14' in the slot 14 for a second revolution.

5 As will be seen in Fig. 1, the left hand side of the slot 14 is open, and adjacent this open space I provide a ratchet 17 fixed on a rotary shaft 18 which extends transversely in a suitable enlarged recess in the drum 1. This shaft 10 is provided with four equally spaced resilient projections 19, each terminating in a curved end adapted to successively engage the flat face of a coin 14' in the slot 14 upon the rotation of the shaft 18. The plunger 15 carries an upwardly 15 projecting resilient pawl member 20, the upper end of which is adapted to engage the teeth of the ratchet 17. At the opposite side of the ratchet 17, I provide a pivoted pawl 21 normally urged into engagement with the teeth of said ratchet 20 by a spring 22 to prevent the reverse rotation 20 of the ratchet and shaft 18.

Thus, upon rotating the drum 1 in clockwise direction by the handle 6, the coin 14' engages the underside of the arm 9 to release the lug 11 25 from the recess 12, and simultaneously therewith, the pressure on spring 16 brought about by the engagement of the coin with the arm 9, causes the plunger 15 to move downwardly and with it the pawl 20. This rotates the ratchet 17 30 and shaft 18 and brings the nearest resilient projection 19 into engagement with the flat side of the coin 14', the pawl 21 maintaining such engagement until the further rotation of the ratchet. The coin 14' now having released the 35 lug 11 from the recess 12 in the drum, permits a complete revolution of the drum, and as said drum starts its second revolution, the coin 14' having been retained in the recess 14 by the action of the resilient projection 19, again engages the arm 9 to release the lug 11 a second time. The plunger 15 is again moved downwardly 40 against the spring 16, this time having engaged the next tooth on the ratchet 17, and rotates the ratchet to a point where the resilient projection 19 disengages the coin. Hence, when the 45 coin reaches the underside of the drum during the second rotation thereof, it drops from the slot 14 into the collecting receptacle, and when the second rotation is completed, the lug 11 has again engaged the recess 12 to prevent further rotation 50 of the drum.

These projections 19 are so arranged that upon the rotation of the ratchet, one of said projections is alternately brought into and out of engagement with a coin in slot 14. Thus, upon the insertion of a coin a second time, the operation just described is repeated.

Near the end of the drum adjacent the handle 6, I provide a third coin receiving slot 23 adapted 60 to receive a coin of still higher denomination, such for example as a twenty-five-cent piece 23'. This slot is provided with a plunger 24 and spring 25 as in the case of the slot 14, but instead of the projections 19 just described in connection 65 with the ratchet 17, I provide adjacent the slot 23 a ratchet 26 rotatably mounted on a shaft 27 which carries a rotary disc 28. The periphery of this disc is provided with a series of brush-like resilient projections 29 which project radially 70 therefrom and cover substantially four-fifths $\frac{4}{5}$ ths of the periphery of said disc, the remaining fifth $\frac{1}{5}$ th of the disc being a bare peripheral space as shown at 30 in Fig. 1.

The plunger 24 is provided with an upwardly 75 projecting resilient pawl 31 adapted to engage

the teeth of the ratchet 26, and on the opposite side of the ratchet 26 I provide a pivoted pawl 32 normally forced by spring 33 into engagement with the teeth of the ratchet to prevent the reverse rotation thereof.

Thus, in the operation of this device by the insertion of a twenty-five cent coin 23' in the slot 23, the periphery of the coin engages the underside of the arm 9 to release the lug 11 from the recess 12, and simultaneously the plunger 24 1 is moved downwardly which in turn rotates the ratchet 26 and disc 28 one-fifth of a revolution to bring a portion of the brush-like surface of the disc into contact with the flat side of the coin 23'. This retains the coin in the slot 23 1 as the drum 1 completes five rotations, each rotation advancing the ratchet one-fifth of its circumference until the last rotation of the drum brings the blank space 30 adjacent the coin 23'. Hence, on this last rotation, as the coin reaches 20 the underside of the drum 1, it is permitted to drop into the coin receptacle.

The modified form of my invention shown in Fig. 3 operates essentially under the same principle as that just described but the specific structure of the elements is somewhat different. In this figure, I have shown the coin controlled mechanism as applied to a vending machine for delivering packages or articles from a magazine 34 by means of a plunger 35 pivoted to a delivery 30 arm 36 hereinafter described in connection with the coin controlled mechanism.

As in the case of the structure just described, this modified form comprises a rotary drum 1 having one or more coin receiving slots 37 in its 35 periphery, each adapted to receive a coin 37'. The drum 1 is recessed as at 38 adjacent each coin receiving slot 37 and in this recess I provide an arm 39, its lower end pivoted as at 40 on a transverse shaft, the upper end of said arm 39 40 lying adjacent the periphery of a coin in the slot 37 and being curved to correspond substantially to the periphery of said coin. This arm 39 is normally held out of engagement with the periphery of the coin 37' by means of a spring 41 40 so as to permit entrance of a coin into the slot.

A ratchet 42 is mounted on a transverse shaft 43 adjacent the intermediate portion of the arm 39, said shaft being provided with a plurality of resilient projections 44 similar in all respects to 50 the projections 19 in Fig. 1 except that instead of engaging the coin as in the former structure, in the modified form, the projections 44 engage the edge of the arm 39 to retain the latter in engagement with the periphery of a coin 37' as will 55 hereinafter appear. The arm 39 is provided adjacent its fulcrum 40 with an upwardly projecting member 45 adapted to serve as a bearing support for the pivoted resilient pawl 46, the upper end of which is adapted to engage the teeth 60 of a ratchet 42. This pawl is formed integral with a projecting arm 47 which is arranged at such an angle with respect to the pawl that it normally extends beyond the periphery of the drum 1 in line with a stationary abutment 48 65 suitably secured to the frame of the machine. A spring 49 normally urges the arm 47 downwardly and in turn releases the pawl 46 from engagement with the teeth of the ratchet 42. A second pivoted pawl 50 under the tension of spring 51 70 prevents reverse rotation of the ratchet 42.

Adjacent the periphery of the drum 1, I provide a rocker arm 52 fulcrumed at 53, the upper end of said arm lying in the line of rotation of the 75 projecting end of the coin engaging arm 39, its 75

opposite end being pivoted as at 54 to the end of the delivery arm 36.

In this modified form of my invention, if the drum 1 is rotated in the absence of a coin from the slot 37, the arm 39 engages the upper end of the arm 52 but as there is no coin in the slot and nothing to halt the rocking of the arm 39 on its pivot 40, the arm 52 forces the arm 39 inwardly and with it carries the projecting arm 41 into the recess 39 so that it fails to engage the stationary abutment 48. Thus the delivery arms remain stationary without delivering an article, and the ratchet 42 is unmoved.

On the other hand, with a coin properly inserted in the slot 37, the rotation of the drum 1 brings the arm 39 into engagement with the upper end of the arm 52, and after the arm 39 has moved inwardly to engage the periphery of the coin 37, the arm 52 is rocked on its fulcrum 53 causing the delivery arm 36 and plunger 35 to eject the lowermost article from the magazine 34. It will be noted that the arm 39 has a double function in that it retains the coin 37 in position during two or more rotations of the drum 1 and also serves to prevent wear on the periphery of the coin due to friction.

It is of course understood that in this modified form, the drum is provided with the same number of slots and for the same denomination coins as that described in connection with Fig. 1. Thus the five-cent slot of the modified drum is not provided with the ratchet and projections 42 and 43, and as the drum makes one rotation, the coin drops from the slot into a suitable coin receptacle.

However, when a ten-cent piece is inserted as illustrated in Fig. 3, simultaneously with the rotation of the drum and engagement of the arms 39 and 52, the projecting arm 41 engages the stationary abutment 48 and rocks the pawl 46 downwardly to rotate the ratchet 42 and shaft 43 to a point where one of the projections 44 engages the adjacent edge of the arm 39 to retain the coin engaging portion thereof in contact with the periphery of the coin 37, the ratchet 50 preventing the release of said coin until the second rotation of the drum 1 has commenced.

It will be understood that this same principle of operation is employed in connection with the third or twenty-five-cent slot; a brush-like disc being provided to insure the proper number of operative engagements of the arm 39 with the arm 52.

It will thus be seen that I have provided a novel and efficient coin controlled mechanism which may be employed in various capacities such as vending machines in department stores, fruit stands and liquid dispensing establishments, whereby a customer may purchase any desired quantity of merchandise by inserting the proper denomination coin.

It will of course be understood that various changes may be made in the specific structure of the elements herein described. For example, instead of employing a handle 6 for rotating the drum 1, an electric motor may be installed, and furthermore, although I have shown only three coin slots in the drum, more or less may be employed within the concept of my invention.

From the foregoing it is believed that the advantages and operation of my invention may be readily understood by those skilled in the art without further description, it being borne in mind that numerous changes may be made in the details disclosed without departing from the

spirit of my invention as set out in the following claims.

What I claim and desire to secure by Letters Patent is:

1. Coin controlled mechanism for vending machines comprising a rotary member, means for rotating the same, a coin recess in said rotary member, a pivoted lever associated with said rotary member and engageable by a coin in said recess for controlling the operation of a vending machine, a device carried by said rotary member and adapted to intermittently prevent the displacement of said coin during a predetermined number of revolutions of said rotary member and to release the same upon the last of said revolutions, and ratchet means operable upon the rotation of said rotary member for operating said device. 5

2. Coin controlled mechanism for vending machines comprising a rotary member, means for 20 rotating the same, a coin recess in said rotary member, a lever pivotally mounted in a transverse slot in said rotary member and adapted to be swung into said recess, means for causing the free end of said lever to normally project radially 25 beyond the periphery of said rotary member, a second pivoted lever mounted adjacent the periphery of said rotary member with one end thereof normally lying in close proximity thereto, its other end being operatively associated with a 30 vending device, said first named lever having a coin engaging portion adjacent its free end, whereby when a coin is inserted in said recess and said rotary member is rotated, the free end of said first lever is caused to abut the adjacent 35 end of said second lever to cause the operation of said vending device, and means carried by said rotary member for preventing the displacement of said coin during a predetermined number of rotations of said rotary member, said last 40 named means being adapted to release said coin after a predetermined quantity of merchandise has been vended, whereby the vending of further merchandise is prevented. 45

3. In a coin controlled mechanism for vending machines including a rotary member, means for rotating the same, a coin recess in said rotary member and a pivoted lever engageable by said coin for controlling the operation of a vending device, means for preventing the displacement of 50 a coin from said recess during a predetermined number of rotations of said rotary member, comprising a ratchet rotatably mounted in said rotary member and carrying a plurality of resilient projections adapted to successively exert a pressure against said coin to retain the same in said recess, a pawl member associated with said ratchet and operable by the rotation of said rotary member to intermittently cause the partial rotation of said ratchet, whereby said resilient projections are successively brought into and out 55 of operative position. 60

4. Apparatus as claimed in claim 3 wherein said resilient projections are adapted to directly engage said coin to prevent its displacement. 65

5. Coin controlled mechanism for vending machines comprising a rotary member, means for rotating the same, a coin recess in said rotary member, a lever pivotally mounted in a transverse slot in said rotary member and adapted 70 to be swung into said recess, means for causing the free end of said lever to normally project radially beyond the periphery of said rotary member, a second pivoted lever mounted adjacent the periphery of said rotary member with one end 75

thereof normally lying in close proximity thereto, its other end being operatively associated with a vending device, said first named lever having a coin engaging portion adjacent its free end, whereby when a coin is inserted in said recess and said rotary member is rotated, the free end of said first lever is caused to abut the adjacent end of said second lever to cause the operation of said vending device, means carried by said rotary member for preventing the displacement of said coin during a predetermined number of rotations of said rotary member, said means comprising a ratchet rotatably mounted in said rotary member and carrying a plurality of resilient projections adapted to successively engage said first named lever to retain the coin engaging portion of the latter in engagement with a coin in said recess, and a pawl member associated with said ratchet and operable by the rotation of said rotary member to intermittently cause the partial rotation of said ratchet, whereby said resilient projections are successively brought into and out of operative position.

6. Coin controlled mechanism for vending machines comprising a rotary member, means for rotating the same, a coin recess in said rotary member, a lever pivotally mounted in a transverse slot in said rotary member and adapted to swing into said recess, means for normally causing the free end of said lever to lie outside of said recess and project beyond the periphery of said rotary member, means operable by said free end upon the rotation of said rotary member for actuating a vending device, said lever having a coin engaging portion adjacent its free end, whereby when a coin is inserted in said recess and said rotary member is rotated, the free end of said lever is retained in operative position, and means carried by said rotary member for preventing the displacement of said coin during a predetermined number of rotations of said rotary member, said last named means being adapted to release said coin after a predetermined quantity of merchandise has been vended, whereby the vending of further merchandise is prevented.

7. Apparatus as claimed in claim 6 including a ratchet rotatably mounted in said transverse slot adjacent said lever, said ratchet being provided with at least one resilient projection adapted to engage said lever upon the rotation of said ratchet, a pawl member fulcrumed on the hub of said lever and movable therewith, said pawl being adapted to engage said ratchet when said lever is in its normal operative position, an arm fixed to said pawl and adapted to project beyond the periphery of said rotary member when said pawl

and lever are in operative position, an abutment adjacent the periphery of said rotary member and arranged in the line of movement of the projecting arm of said pawl, whereby upon the rotation of said rotary member, said pawl will be actuated to cause the partial rotation of said ratchet.

8. Coin controlled mechanism for vending machines comprising a rotary member, means for rotating the same, a detent normally engaging said rotary member to prevent the complete rotation thereof, a coin recess in said rotary member and adapted to retain a coin with a portion thereof projecting beyond the periphery of said rotary member and in line with said detent whereby upon the partial rotation of said rotary member said coin will engage and release said detent, a ratchet rotatably mounted in said rotary member adjacent said coin recess and provided with a plurality of resilient projections adapted to successively engage said coin to retain the same in said recess, a plunger in the lower extremity of said recess normally forced outwardly by a spring, said plunger supporting the coin in said recess and being forced inwardly by the contact of said coin with said detent, a pawl operatively associated with said plunger and adapted to engage said ratchet when said plunger is moved inwardly, and a second pawl pivoted to said rotary member for locking said ratchet against reverse rotation.

9. Coin controlled mechanism for vending machines comprising a rotary member, means for rotating the same, a plurality of recesses in said rotary member for receiving coins of different denominations, a lever pivotally mounted in a transverse slot in said rotary member adjacent each of said recesses and adapted to be swung into the respective recesses, means for causing the free end of each lever to normally project radially beyond the periphery of said rotary member, means adjacent each of said free ends and actuated thereby for operating a vending device, each of said levers having a coin engaging portion adjacent its free end, whereby when a coin is inserted in the respective recess and said rotary member is rotated, the free end of said lever is caused to actuate said vending device, and means carried by said rotary member adjacent certain of said levers for preventing the displacement of said coins during a predetermined number of rotations of said rotary member, the number of rotations permitted varying in accordance with the denomination of the coin inserted.

CHARLES WALKER. 55
